CHAIR

Filed Nov. 3, 1924

UNITED STATES PATENT OFFICE.

WILLIAM S. FERRIS, OF ELKHART, INDIANA.

CHAIR.

Application filed November 3, 1924. Serial No. 747,428.

This invention relates to improvements in chairs and it consists in the matters herein-after described and more particularly pointed out in the appended claims.

- 5 The primary object of the invention is to provide a chair wherein the seat is so mounted as to be capable of a limited lateral rocking or tilting movement with respect to the supporting standard or post.
- 10 A further object of the invention is to provide an improved seat frame which is so mounted on the swivelling post or stem that upon the occupant shifting his or her position or leaning to one side or the other of the seat, 15 the same will rock or tilt in that direction under the weight of the occupant and against the action of a resilient means which acts to return the seat to its normal position.

These objects of the invention, as well as the 20 many advantages thereof, will more fully appear as I proceed with my specification.

In the drawing:

- Fig. 1 is a view in front elevation of a 25 swivelling chair embodying my invention.
- Fig. 2 is a bottom plan view of the seat frame.
- 30 Fig. 3 is a detail vertical sectional view through the connection between the seat frame and its associated post or stem, the plane of the section being indicated by the line 3-3 of Fig. 1.

The chair as illustrated and described herein is a metallic chair of the swivelling type and is one especially adapted for use by machine operators, such as of billing machines, 35 linotype machines and other keyboard machines wherein the operator is called upon at times to manipulate certain parts of the machine which are beyond the ordinary reach of the operator while sitting in the normal position in the chair. Such chairs are usually provided with casters and in some cases the chair is moved laterally on its casters by a movement of the feet and body to reach the 40 particular part of the machine to be manipulated. This method is preferred to the stretching for a long reach but it is tiresome, it wastes time, detracts the attention of the operator from his or her work and in some 45 cases results in tipping the chair over.

The chair of my present invention is so constructed as to eliminate the above disadvantages and to rock or tilt laterally under the shifting or leaning of the occupant so that the

parts of the machines operated and heretofore 55 inaccessible in the ordinary reach, may be readily manipulated, and this without calling for a tiresome effort on behalf of the operator.

Referring now in detail to that embodiment 60 of the invention illustrated in the accompanying drawing 1 indicates the supporting standard or base of the chair and 2 indicates the seat frame. The standard or base as herein shown comprises a plurality of legs 3, the top 65 upright ends of which are held together in a grouped relation by means of bracket members 4-4 and a nut stop member 5. The bottom ends of said legs are suitably formed to increase the spread of said legs and to said 70 bottom ends are secured the usual casters 6. Between the top ends of said grouped legs and resting on the member 5 is a nut 7 into which the bottom end of a post 8 is threaded in the usual manner providing a bearing for said 75 post.

To the top end of said post is fixed the open 80 rectangular frame 9 of the seat 2. The seat frame is made up of edgewise arranged strap iron and includes front and rear members 10 and 11 and side members 12-12. Said side members are made integral with said rear member and define the depth of said seat frame and the front member 11 has rearwardly extending end portions 13-13 which are 85 suitably attached to the front ends of the side members 12-12. The front and rear members 10 and 11 which are slightly bowed downwardly between their ends, are further connected together, near the end members 12-12 90 by means of flatwise arranged straps 14-14. Said straps engage or rest upon the top edges of said front and rear members and have downwardly bent end extensions 15-15 which are preferably riveted to said front and 95 rear end members. Resting upon said straps 14-14 is a cushioned seat 16 and operatively connected to the side members 12-12 is an adjustable back rest 17 which need not be described in further detail as it forms no particular part of the present invention.

Incorporated in the seat frame 9 are front and rear substantially V-shaped brace bars 18-18. Each brace bar has angularly disposed side members 18a-18a which extends 105 substantially radial from the center of the seat frame as defined by the post 8 and the outer ends thereof have ears 19-19 which are

riveted to the front and rear members 10 and 11 near the seat supporting members 14—14. The inner ends of the members 18^a—18^a are connected together by means of parts 20—20 which, while spaced a suitable distance upon each side of the post 8, are parallel with the front and rear members 10 and 11 of the seat frame.

Interposed between said parts 20—20 is 10 a transversely extending channel member 21 which includes a top web 22, front and rear flanges 23—23, each with an inturned extension 24, the web 22 being spaced a slight distance below the bottom of the seat 16. Within 15 said channel member is located a flat rectangular block 25, which engages at its front and rear with the flanges 23—23 of said channel member. Said block rests at its bottom upon the flange extensions 24—24 of the 20 channel and is of a thickness less than the height of said channel so as to leave a space 26 between it and the web of said channel member. In said block is provided a hole 27 to receive the top end of the post 8, a bolt 28 passing through the parts 20—20, flanges 23—23, block 25 and post 8 and operatively connecting said parts together. A nut 29 is 25 associated with said bolt.

30 indicates a flat resilient or spring bar 30 which extends parallel with but midway between the front and rear members of the seat frame. Said spring bar extends through the space 26 between the block 25 and the web 22 of the channel member 21 and engages at its 35 ends with the underside of the members 14—14, said bar being slotted near its ends as at 31 for the passage of bolts 32 and associated nuts which secures said bar ends to said members 14.

40 When the chair is occupied, by shifting the weight of the body by leaning toward one side or the other of the seat frame, said frame will rock or tilt about the bolt 28 and will flex one end of the spring bar 30 downwardly 45 and the other end upwardly, the rocking or tilting movement being relatively short and limited by the engagement of the lateral ends of the channel web 22 with the bottom of the chair seat. As soon as the weight of the body 50 is again shifted to the normal position upon the seat it, of course, instantly returns to its normal horizontal position.

55 My improved chair possesses many advantages. In actual use by keyboard machine operators, time and effort are saved in making the reach often times required in operating such machines as it eliminates the necessity of shifting the entire chair to one side or the other of the normal position it occupies 60 with reference to the machine being operated.

Said lateral tilting of the seat frame in no manner interferes with the intended swiveling action of the seat. The seat frame and parts associated therewith are light in weight, yet strong and rigid and may be produced at 65 a relatively low cost because machine and pattern work is reduced to a minimum and said frames may be easily assembled by unskilled labor.

While in describing my invention, I have 70 referred to certain details of construction, form and arrangement of parts, the same is for the purpose of illustration only and, therefore, I do not wish to be limited thereto except as may be pointed out in the appended 75 claims.

I claim as my invention:

1. A chair embodying therein, a rotatably mounted post, a rectangular seat frame, a block on the top end of the post, a channel 80 member connected to said seat frame and in which said block is arranged, means pivotally connecting said block, post and channel member together and a spring bar interposed at its middle between said block and channel 85 and operatively connected at its ends to said seat frame.

2. A chair embodying therein, a rectangular seat frame, brace bars forming a part of said frame and having parts arranged near the 90 center of the seat frame, a channel member arranged between said parts, a rotatably mounted post, a block on the top end thereof and arranged in said channel, a pivot member connecting said block, channel member and 95 seat frame together and a flat spring bar having its middle parts interposed between said channel member and block and operatively connected at its ends to said seat frame.

3. A chair embodying therein a post, a seat 100 frame including parts arranged near the center thereof and parallel with the front and rear of the seat frame, a flat strap at each end of the seat frame, a downwardly facing channel member disposed upon the top of 105 the post, means parallel with said straps for pivotally connecting the central parts of the seat frame to said post for a laterally tilting movement, a spring bar engaged with its midportion between the top of the post and said 110 channel member and means providing a screw and slot connection between the ends of said spring bar and said straps to provide a limited guided movement therebetween, said spring bar acting to resist the lateral tilting 115 of the seat frame on the top end of the post.

In testimony whereof, I have hereunto set my hand, this 28th day of Oct., 1924.

WILLIAM S. FERRIS.
